UNITED STATES PATENT OFFICE.

FRANK A. HALLECK, OF OAK PARK, ILLINOIS, ASSIGNOR TO SULLIVAN MACHINERY COMPANY, A CORPORATION OF MASSACHUSETTS.

HEAT-EXCHANGE DEVICE.

1,401,717.

Specification of Letters Patent. Patented Dec. 27, 1921.

Application filed November 28, 1917. Serial No. 204,459.

To all whom it may concern:

Be it known that I, FRANK A. HALLECK, a citizen of the United States, residing at Oak Park, in the county of Cook and State of Illinois, have invented certain new and useful Improvements in Heat-Exchange Devices, of which the following is a full, clear, and exact specification.

My invention relates to heat exchange devices, and more particularly to intercoolers for compressors.

It has for its object to cool the air used in a multi-stage compressor in an improved manner. A further object of my invention is to provide an intercooler having an improved construction and arrangement of air and cooling fluid passages whereby the cooling effect and the resultant efficiency of such a compressor is materially increased. A still further object of my invention is to provide an intercooler of improved and simplified construction wherein the cooling effect is greatly augmented, the air being brought into contact with the cooling elements during its passage throughout a materially extended path, and the cooling elements themselves being of an improved construction whereby a greatly increased cooling surface is rendered available. These and other objects and advantages of my improvement will, however, hereinafter more fully appear.

In the accompanying drawings, I have shown for purposes of illustration one embodiment which my invention may assume in practice, illustrating the same as applied to use in connection with a well known type of compressor known as the angle compound, although it will be understood that my invention is not limited to use in conjunction therewith.

In these drawings,—

Figure 1 is a side elevation showing such a compressor equipped with my improvement, the intercooler casing being broken away to facilitate illustration.

Fig. 2 is a detail end elevation of the intercooler with the cover plate removed and showing the several cooling units.

Fig. 3 is a longitudinal sectional view of the intercooler showing the various passages leading to and around the several cooling units therein.

Fig. 4 is a detail plan view of one of the cooling units.

In this illustrative construction, it will be observed that I have shown a compressor of the angle compound type comprising a base 1 having suitable cylinders 2 and 3 disposed at right angles to one another, suitable pistons 4 and 5 being movable in these cylinders and connected to the usual crank shaft 6 which is adapted to be driven from any suitable source and, as is customary, is provided with a flywheel 7. As in the usual angle compound construction, the intercooler is located between the cylinders 2 and 3 in such a manner as to receive the air from the low pressure cylinder 2 and deliver the same to the high pressure cylinder 3 after the same has been cooled during its passage through the intercooler. In the construction illustrated, the intercooler casing is indicated at 8 as suitably supported on the base 1 and connected through a suitable connection 9 forming its air inlet, to the low pressure cylinder 2, and also connected through a suitable passage 10 forming its air discharge, to the high pressure cylinder 3.

In my improved construction, it will be observed that the intercooler casing 8 is substantially rectangular in cross section and enlarged, in such a manner as materially to increase the area available, at the same time that it is still possible to accommodate the intercooler compactly within the outlines of the machine. It will also be observed that the intercooler casing 8 is provided with a series of horizontally disposed shelves 90 between its top and bottom, two of the same being herein shown at 11 and 12, which are adapted to divide the intercooler casing into a plurality of compartments 13, 14, and 15. As illustrated, these compartments 13, 14 and 15 are adapted to communicate, the lower of the same, *i. e.* the compartment 15, communicating with the inlet 9 through a suitable opening or port 16, while the compartment 15 communicates with the compartment 14 through a suitable opening or port 17, and the compartment 14 communicates with the compartment 13 through a suitable opening or port 18, the latter compartment communicating with the discharge 105 through a suitable opening or port 19. It will also be observed that these several openings are arranged in staggered relation at opposite ends of the casing 8 in such a manner as to enable a flow of air from the low 110

pressure cylinder to pass up into one end of the compartment 15, and longitudinally thereof up through the opening 17 into the opposite end of the compartment 14, longitudinally of that compartment to the other end thereof, up through the opening 18 into the compartment 13, and longitudinally of that compartment to the outward opening 19 leading to the discharge. There are thus 10 provided a plurality of parallel passes in series for the air to be cooled. Attention is also directed to the fact that in my improved construction one end 20 of the casing 8 acts to permanently close one end of each of these 15 compartments, while the other ends of the same are adapted to be closed by the cooling units hereinafter described.

These units, as illustrated in Fig. 4, each 20 comprise a series or bundle of small, longitudinally disposed, spaced tubes or pipes 21 so arranged as to permit access of the air to practically their entire area and also to permit the flow of the cooling medium from one end of each unit down through certain 25 pipes thereof and back through other pipes to an outlet point located adjacent its inlet. More specifically, each of these units is shown to be provided with an end plate 22 perforated at 23 to permit fluid flow through

30 the pipes and adapted to be attached over and close the open end of its compartment 13, 14, or 15 when the unit is disposed longitudinally in the same. At its opposite end, each of these units is also provided 35 with a smaller end member or header 24 adapted to be slipped into a compartment and likewise provided with suitable openings 25 adapted to receive the pipes, this member 24, however, also being provided 40 with a passage 26 to enable the cooling medium to pass out of one set of pipes and guide and direct it into the other set for its reverse flow. In a preferred form, these members 22 and 24 are each connected to 45 the several pipes 21 as, for example, by slightly expanding the ends of the latter as is usual in ordinary boiler practice. As shown, the several pipes are also spaced apart and connected to the member 22 50 through a series of threaded longitudinally extending bolts 27 operatively connected to a plurality of transversely disposed baffle plates 28, perforated to permit the free passage of the pipes and the free longitudinal 55 expansion and contraction thereof. As shown, these plates 28 are spaced apart by short lengths of spacing pipes 29, surrounding the bolts 27, and are clamped in position by nuts 30 on their ends, the same being 60 disposed in staggered relation at different points along the length of the pipes 21 in such a manner as to cause the air passing from one end to the other of each compartment to take a circuitous path, alternately 65 traveling over and under the different baf-

fles as it passes from the inlet of the compartment to the outlet thereof. Co-operating with these baffles, it will also be observed that I have provided spaced, transversely disposed ribs or baffles 31 on the interior of 70 the top of the casing 8 and on the under side of the shelves 11 and 12, which are disposed in alignment with the baffles 28 and act therewith to direct the air between the cooling pipes, these baffles 31 being particularly effective in preventing any uninterrupted flow of air above the cooling surfaces of the units. Thus, it will be observed that the cooling medium is passed longitudinally 75 in opposite directions through each compartment, finding an outlet at a point adjacent its inlet, while the air to be cooled passes in a circuitous path through each compartment in such a manner that it is brought into contact throughout an exceedingly long path with practically every inch 80 of cooling area, and thus is effectually cooled.

In order to supply the cooling medium to the different pipes 21 of the several units 90 and to enable the same to flow continuously from one set of pipes to the other and through the machine, it will be observed that I have provided a pipe 32 extending from the water jacket 33 of the low pressure cylinder 95 up nearly to the level of the top of the compartment 13 and at a point adjacent the air inlet end thereof. There, it will be observed that this pipe 32 communicates by means of a longitudinally extending passageway 34 with an upper chamber 34 in a removable chambered cover plate 35 disposed over the open end of the intercooler and inclosing the end plates 22 of the several cooling units. As illustrated, this plate 100 35 is provided with a plurality of spaced, horizontally disposed ribs 36 adapted to engage each of the plates 22 at a point intermediate its ends. Thus, it will be observed 105 that when the cover 35 is clamped in position by suitable means, such as the clamping bolts 37, each unit is held securely in place and the cooling fluid therefor is automatically divided in such a manner that a continuous flow may be obtained through 110 the unit. As illustrated, these ribs 36 also act to form a plurality of intermediate larger chambers 38 and another smaller chamber 39, corresponding to the chamber 34. This chamber 39, as shown, in turn communicates by means of a passageway 39' 115 with a discharge pipe 40 leading to the water jacket 41 of the high pressure cylinder. 120

In the operation of my improved construction, it will be observed that the air 125 from the low pressure cylinder is caused to pass into and longitudinally of the compartment 15 into the opposite end of the compartment 14, through that compartment, 130

and into the opposite end of the compartment 13, through which it passes longitudinally to the opening 19 leading to the high pressure cylinder. During this travel of the air, it will also be observed that the same is caused to pass around the several baffle plates 28 and 31 in such a manner as to bring the same in contact with each of the several cooling pipes 21 substantially throughout its length. It will also be observed that the cooling fluid enters the intercooler at such a point that the same when coldest is brought into contact with the air when the latter has practically reached its minimum temperature, and that thereafter the gradually warming water is passed reversely along the stream of gradually cooling air, finding an outlet at the point where the air is warmest. Thus, it will be noted that the maximum cooling effect is obtainable, since, as the water even when it leaves the intercooler is always cooler than the air entering the latter, it is enabled to act effectively as a cooling agent at all points throughout its passage through the intercooler. It will also be observed that through the use of a large number of pipes 21 of relatively small cross section, it is possible to multiply the streams of water passing through the intercooler and thus increase the cooling area available, and that through the provision of a construction of rectangular cross section it is not only possible thus to provide a large cooling area, but also to provide a cooling means which substantially fills the intercooler casing without in any way interfering with the flow of air therethrough.

As a result of my improvement it has been found that not only is the temperature of the air entering the high pressure cylinder materially reduced, but that as a result the efficiency of the compressor has been materially increased. By the use of my improved construction, wherein the cooling elements are divided into units, it will also be noted that it is possible for the same to be very readily assembled or removed when desired, any unit being readily withdrawn whenever the cover plate 35 is detached. Obviously, the different members going to make up each of these units may also be very readily assembled and cheaply manufactured, so that at the same time that it is possible to increase the capacity for a compressor of a given size, it is also possible to maintain a relatively low manufacturing cost. These and other advantages of my improvement will, however, be clearly apparent to those skilled in the art.

While I have in this application specifically described one embodiment which my invention may assume in practice, it will be understood that the invention is not limited

to embodiment in the particular form illustrated, and that the same may be modified and embodied in other forms without departing from its spirit or the scope of the appended claims.

What I claim as new and desire to secure by Letters Patent is:

1. An intercooler comprising a casing having parallel superimposed communicating compartments, each of which compartments is closed at one end and a cooling unit carried in each of said compartments and projecting thereinto from the open end thereof. 75
2. An intercooler comprising a casing having parallel superimposed compartments communicating with one another at their opposite ends, and a removable cooling unit carried in each of said compartments and providing for a circulation of cooling medium in opposite directions therein. 80
3. An intercooler comprising a casing having a closed end and a series of superimposed open ended communicating compartments, and a cooling unit carried in each compartment and closing the end thereof. 85
4. An intercooler comprising a casing having a plurality of superimposed communicating compartments, and means for directing a cooling medium in opposite directions to each of said compartments, said means comprising a plurality of removable cooling units. 90
5. An intercooler comprising a casing having a closed end and a series of superimposed open ended communicating compartments, a cooling unit carried in each compartment and closing the end thereof, and means for directing a cooling medium consecutively through said units. 100
6. An intercooler, a casing comprising a plurality of parallel communicating air compartments, and means for cooling the air therein comprising means for providing a series of finely divided cooling streams passing consecutively through said compartments including a plurality of separately removable cooling units disposed one in each compartment. 110
7. An intercooler comprising a casing of substantially rectangular cross section and having a plurality of parallel communicating compartments formed therein, and a plurality of cooling units disposed in said compartments, each comprising a series of spaced cooling tubes coöperating to form a unit of substantially rectangular cross section substantially filling its compartment and each removable without removal of any other. 120
8. An intercooler comprising a casing having a closed end, transverse longitudinally extending ported partitions therein forming a series of passes connected with 130

each other alternately at opposite ends, and a series of cooling units, one in each pass, comprising closure plates for the ends of said compartments, cooling fluid tubes secured in said closure plates, and headers slidably mounted in said compartments.

9. An intercooler comprising a casing having a closed end, transverse longitudinally extending ported partitions therein forming a series of passes connected with each other alternately at opposite ends and a series of cooling units, one in each pass comprising closure plates for the ends of said compartments, cooling fluid tubes secured in said closure plates and headers slidably mounted in said compartments, and a cover plate for the end of said intercooler opposite the closed end thereof provided with partition plates coöperating with the headers to effect a reversal of flow of cooling fluid in each of said cooling units.

10. An intercooler comprising a casing having an inlet compartment and an inlet connection thereto, an intermediate compartment communicating with said inlet compartment at the opposite end of the latter from said inlet connection, a discharge compartment communicating with said intermediate compartment at the end thereof adjacent the inlet end of said intercooler, said discharge compartment having a discharge opening at the end thereof remote from the inlet thereto, and separate cooling units in each of said compartments, said cooling units being arranged in series.

11. An intercooler comprising a casing having a closed end, longitudinally extending partitions in said casing dividing the same into a plurality of parallel compartments, said partitions being provided with

openings adjacent the opposite ends of said casing, said openings being disposed at opposite ends of adjacent partitions, cooling units located in each of said compartments, said cooling units comprising plates closing the open ends of said compartments, tubes secured in said plates and headers with which said tubes communicate at their opposite ends, and a front plate for said casing having partition ribs formed thereon, said ribs abutting said end plates adjacent the middle portions thereof.

12. An intercooler comprising a casing having a closed end, said casing being divided into a plurality of parallel, serially arranged, communicating, open ended compartments by longitudinally extended, ported partition member, cooling units disposed in each of said compartments and each comprising a header freely slidable in its respective compartment, a series of tubes communicating with said header, and a closure plate in which said tubes are mounted at their opposite ends, said closure plate serving to close the open end of said compartment, and baffles arranged in staggered relation with respect to said cooling tubes and held in fixed relation with respect to said closure plate, and a cover plate at the end of said intercooler casing opposite said closed end, said cover plate having transversely extending partitions formed thereon dividing the same into a series of compartments, said partitions being disposed adjacent the median lines of said closure plates whereby a reverse flow occurs in each cooling unit and a serial flow through the series thereof.

In testimony whereof I affix my signature.
FRANK A. HALLECK.
